[57] ABSTRACT

A method and system for coating yarn ends or the like on the entire outer surface so as to prepare the yarn for subsequent textile treatments and/or change the characteristics of the same. The yarn end is moved in a direction generally along its axis transversely across a narrow, elongated surface of the coating liquid and as it moves across the surface of the coating liquid, the yarn end is rolled so that the coating liquid is precisely applied to the entire outer surface of the yarn end. The system and method may be utilized with existing textile equipment, such as spinning, twisting and roving frames or winding machines and the like, without material modification to such equipment.

YARN COATING SYSTEM

The present invention relates to an improved system for coating yarn ends or the like with a coating liquid so that the same can be prepared for subsequent textile treatments and/or changes in its physical characteristics.

PRIOR ART

Heretofore, many different processes and apparatuses have been used to prepare yarn for subsequent textile treatments and/or for changing the characteristics of the yarn for a particular end use. In some instances the yarn was completely immersed in a bath of liquid and this treatment required draining of excess liquid therefrom and utilization of drying equipment since the yarn was usually saturated. Oftentimes the resulting coating was not uniform and thus interfered with subsequent treatments of the yarn, as well as providing a variation in finishes of the resulting end products. In other instances where it was desired to coat the yarn with a particular coating material instead of applying the coating in liquid form, the yarn was passed over the coating material in solid state, for example wax or the like, in an effort to pick up some of the material on the yarn. Special equipment was required and constant maintenance of the equipment was necessary if anything like a uniform coating was to result.

None of the various processes and apparatuses used for coating yarn were particularly adaptable for use in or with existing textile machinery such as winding machines and spinning, twisting and roving frames. Additionally, such prior processes and systems wasted a good amount of the coating material as either too much was applied initially and the excess had to be removed, or too much was lost in the actual application of the coating material to the yarn.

SUMMARY OF THE INVENTION

According to the present invention, yarn ends or the like, are coated with a material in liquid form, the coating being accomplished by the end being moved across the surface of a narrow elongated path of a desired coating liquid, and while being moved across such surface, the end is rolled or rotated so that its outer surface is uniformly and completely coated. More particularly, the coating liquid is supplied to the path in a metered amount, dependent on the speed of the end across the same, and of the end's pick up capabilities, so that only an amount of liquid substantially equal to the amount picked up is replaced in the path, thereby eliminating waste of the coating liquid. The method and system of the present invention may be easily incorporated into existing textile machinery without major modification of such machinery, as the method and system is independently operable and incorporates means for collecting excess coating liquid discharged when the textile machinery is inoperative or when no yarn end is actually being coated.

The yarn may be coated with any of a various number of materials in liquid form, depending upon the subsequent textile treatments to be accomplished and/or depending upon whether or not certain physical characteristics of the yarn are desired to be changed. For example, certain textile equipment used in subsequent textile processes require the yarn to be lubricated and therefore oil or wax emulsions may be used as the coating liquid. In other situations, it may be necessary to tint or dye the yarn before subsequent textile treatment of the same, and in these situations tint and dye emulsions may be used as the coating liquid. Where it is necessary to provide a twist setting conditioner to the yarn, or in some instances to change the physical characteristics of the yarn, such as increasing the tensile strength by elongation of the fibers, then oils, wetting agents, such as water, or an emulsion of soap and water, or polymers or polymer solution such as polyvinyl alcohol, or solvents, may be used as the coating liquid to relax the tightly twisted fibers, or otherwise change the fibers. Sometimes it is desirable to apply a size coating such as starch or the like to the yarn to reduce scuffing and pilling of the

outer surface fibers of the same in subsequent treatments, and in this instance, size in liquid form may be coated to the exterior of the yarn.

In each instance of the application of the coating to the yarn end by the above-mentioned materials, the system or apparatus of the present invention results in just a sheath coating on the entire outer surface of the yarn end, without the coating permeating the entire body of the yarn end. This results because the coating liquid is effectively wiped onto the yarn end's outer surface, without the yarn end being completely submerged into the liquid.

DESCRIPTION OF THE DRAWINGS

15 The above advantages of the present invention will be more apparent in the following specification, claims and drawings, in which:

FIG. 1 is a schematic side view of one system for accomplishing the method of the present invention, the system being incorporated in a typical winding machine;

20 FIG. 2 is a schematic top fragmentary plan view of the system of FIG. 1;

FIG. 3 is an enlarged sectional view partly in elevation and taken substantially on the line 3-3 of FIG. 2, the view illustrating the tube-like applicator for the coating liquid;

25 FIG. 4 is an enlarged sectional view taken on the line 4-4 of FIG. 3, the view additionally showing the means for collecting excess coating liquid;

FIG. 5 is a schematic side view of a modification of the 30 system of FIGS. 1-4, the system being illustrated as incorporated in a textile frame such as a spinning, twisting, or roving frame;

FIG. 6 is a fragmentary plan view of the balloon ring taken 35 in the direction of the arrow 6 of FIG. 5, the view eliminating the bobbin, traversing ring and traveller for purposes of clarity;

FIG. 7 is a large vertical sectional view taken on the line 7-7 of FIG. 5 and illustrating the balloon ring; and

40 FIG. 8 is an enlarged fragmentary view of a transverse ring and the traveller.

DETAILED DESCRIPTION OF THE INVENTION

Referring now to the drawings wherein like character or 45 reference numerals represent like or similar parts, an improved system for accomplishing the method of the present invention is disclosed in FIGS. 1 and 2 in association with a conventional winding machine generally designated at 10. The winding machine 10 is utilized to unwind yarn from a supply 50 package 12, such as a cake, or the like, the yarn then being wound onto a take-up package 14, such as a cone, bobbin or the like. In this respect the yarn end E is drawn off of the supply package 12 and is passed upwardly through a pigtail eye 16, from which it then travels to, and is wound onto, the take-up package 14, the take-up package being rotated by a 55 positively driven wind-up roll 18. The unwinding of the yarn end E from the supply package 12 provides some twisting action to the yarn end so that, in effect, the yarn end will roll about its axis as it passes from the pigtail eye 16 onto the take-up package 14. Of course, the traversing of the yarn end E back and forth onto the take-up package 14 will also, in effect, assist in the rolling or twisting of the yarn end E, in its movement between the broken line positions for the yarn end, as 60 shown in FIG. 2.

The improved system and method of the present invention is incorporated into the winding machine at a suitable point, such as intermediate the pigtail eye 16 and the take-up package 14, where the yarn end is traversing back and forth in 65 a plane. In more detail, and referring now to FIGS. 1-4 inclusive, the system of the present invention includes tube-like liquid coating applicator member 20 fixedly supported beneath, but in contact with, the yarn end E, travelling between the pigtail eye 16 and the take-up package 14, the 70 axis of the tube-like member being substantially horizontal

and generally transverse to the direction of movement of the yarn end E. The tube-like applicator member 20, as best shown in FIGS. 3 and 4, is hollow with its interior defining a liquid chamber 22. An elongated narrow trough 24 is provided in the upper portion of the exterior of the applicator member 20, and it is over this trough that the yarn end E passes. The trough 24, which has its axis parallel to the axis of the tube-like member 20, extends generally transverse of the direction of movement of the end E over the same, thus the trough defines a narrow, elongated path of liquid presenting a surface for contact with the exterior of the yarn end. The trough 24 communicates with the chamber 22 by means of one or more orifices 26, opening into the bottom of the trough.

One end of the tube-like applicator member 20 is closed, as indicated at 28, whereas the other end is connected by a fitting 30 to supply conduit 32, leading from a manifold 34. The conduit 32 includes a restrictor 36 therein, which provides a means of metering the desired coating liquid supplied under pressure from the manifold 34 into the chamber 22 of the tube-like member 20. The manifold 34 is in turn suitably connected to a coating liquid supply tank 38 by a conduit 39, the liquid L in the tank being placed under a predetermined pressure by supplying compressed air through a line 40 to the upper portion thereof. In more detail, the air supply line 40 is provided with a gauge 42 and a selectively operable pressure regulator 44. By controlling the pressure in the upper portion of the tank 38 to a predetermined value, the metered flow of coating liquid through the restrictor 36, into the tube-like applicator member 20, can be controlled so that a predetermined amount can be discharged from the chamber 22 into the trough 24, the amount discharged being adjusted to an amount sufficient to replace the amount coated onto the yarn E passing over the top of the trough in contact with the surface of liquid therein. This reduces the overflow waste of coating liquid L when actual coating of the end E is being accomplished and also provides a precise quantity of coating for the yarn end E.

When no yarn end E is passing across the trough 24 and is being coated by liquid therein, liquid will still be discharged into the trough, causing the same to flow over the edge and run down the exterior of the tube-like member 20. In order to collect this excess liquid, a U-shaped manifold 46 is positioned under and in alignment with the tube-like applicator member 20 to catch the overflow. Manifold 46 is provided with a drain 48 communicating by means of a conduit 50 with a collection tank 52.

As is conventional, a winding frame 10 usually has a plurality of stations thereon, so that a plurality of supply packages 12 can be unwound simultaneously and respectively wound onto a plurality of take-up packages 14. Consequently, at each station of the winding machine 10 it is necessary to place one of the tube-like applicator members 20, the same being connected to the common manifold 34, for receiving a supply of coating liquid at a predetermined metered rate therefrom. For simplicity purposes, the manifold 46 is made to extend under each of the plurality of the tube-like applicator members 20, the manifold 46 collecting excess liquid from any of the particular applicators and depositing the same into the common collection tank 52.

A planar plate member 54 is fixedly secured to the tube-like applicator member 20, the plate member extending from the discharge side or edge of the trough 24 in a plane common to the top edge of the trough so that the yarn end E, after being coated with the liquid, passes in contact with the plate member. As previously explained, the yarn end E, while moving in a general direction of its axis, is also traversing back and forth along the length of the trough 24, thus having a rolling action and consequently, since it is also in contact with the plate-like member 54, the coating liquid will be further evenly distributed about the entire surface of the yarn end.

Referring now to FIGS. 5-8 inclusive, there is a modification of the system shown in FIGS. 1-4 for also utilizing the method of the present invention. In more detail, the system is

shown incorporated in a textile frame such as a spinning, twisting or roving frame. The textile frame is generally designated at 70 and includes a take-up package 14', which in this case is a bobbin mounted on a spindle and onto which the yarn end E is to be wound. The bobbin may be suitably rotated and, as is conventional, in such a frame 70 there is provided a traversing ring 72 having the usual traveller 74 rotating about the traversing ring at a high rate of speed as the package 14' is being formed from the yarn end E. The yarn end is shown 10 passing through a pair of front drawer rollers 76 and 78 and from there downwardly through the usual pigtail 80. Since the end E is travelling at a relatively high rate of speed, as well as being orbited by the traveller 74, rotating about the traversing ring 72, the yarn end will have a tendency to balloon between 15 the pigtail 80 and the traversing ring 72.

Usually such frames 70 are provided with a balloon control ring 82, the balloon control ring suitably positioned to limit ballooning. In the system of the present invention the balloon control ring 82 is utilized as an applicator for applying a coating liquid to the yarn end E. As shown in FIG. 5, the balloon control ring 82 is suitably fixedly mounted on a standard 84 above the spindle on which the bobbin 14' is mounted and this annular ring confines the balloon of the yarn end E against its inner surface.

Referring now to FIG. 7, it will be noted that the balloon control ring 82 is provided with an annular interior groove 86 defining a chamber for the coating liquid. In the particular environment shown, the groove 86 is formed in a member 88 which may be metallic or plastic, the member 88 being annular and fixedly supported with the balloon control ring 82 to define the inner surface thereof. An annular slit or orifice 90 is provided in the member 88 and it provides communication between the interior of the chamber or groove 86 and the interior surface of the ring over which the yarn end E passes, so that the coating liquid within the chamber can be discharged through the orifice or slit. In other words, the annular elongated slit or orifice 88 defines an elongated thin or narrow path for the coating liquid which presents a surface of such liquid to the yarn end E passing over the interior surface of the balloon control ring 82.

As shown in FIG. 7, a restrictor passageway 36' communicates with the interior groove 86, the restrictor passageway 36' functioning as a metering means for metering coating liquid to the groove or chamber and from the slit or orifice 88. The restrictor passageway 36' communicates through a conduit 32' to a manifold 34 identical with the manifold described in connection with FIGS. 1-4 inclusive. The manifold 34 communicates with the coating liquid supply tank 38, the tank 38 being pressurized in an identical manner to that previously described.

The control of coating liquid from the supply tank 38 to the manifold 34 from which it is metered to the chamber defined by the groove 86 and discharged therefrom through the slit 90 is identical to that previously described in that the rate of flow is such that the supply into the groove 86 is only sufficient to replace the amount of coating liquid pick-up by the yarn E as it passes over the annular slit or orifice 90. The yarn end E, in passing over the slit or orifice 90, will be orbiting in continuous contact with such slit, rather than back and forth as described in connection with FIGS. 1-4 inclusive, but the yarn end E is still rolling or rotating about its axis as it is advanced through the balloon control ring 82 to the traveller 74 and onto the take-up package or bobbin 14'. Thus, a precise amount of coating liquid is applied to the entire outer surface of the yarn end.

Balloon control ring 82 is provided with a second annular groove 92 positioned beneath the orifice or slit 90. The groove 92 is open to the interior surface of the balloon control ring 82 and thus functions as a collection chamber for any coating liquid which may run down the interior surface from the slit 90, when no yarn end E is passing thereover. At least one drain passage 94 communicates with the second groove 92 and extends to a drain manifold 96, which in turn is connected 70 to a collection tank 52.

As will be appreciated, textile frames, like winding machines, are provided with a plurality of stations for operating on a plurality of yarn ends E simultaneously, and consequently, by utilizing the manifold 34 and the manifold 96, the same supply tank 38 and collection tank 52 respectively may be used for each balloon control ring at the various stations.

The terminology used throughout the specification is for the purpose of description, the scope of the invention being defined by the claims.

What is claimed is:

1. A system for uniformly coating the entire outer surface of a yarn end with a coating liquid comprising:
 a liquid applicator including a tube defining a chamber for the coating liquid and having a substantially horizontal axis, said tube having an elongated trough extending axially on the upper exterior portion thereof, said trough being in communication with said chamber and filled with coating liquid therefrom to define a thin elongated surface area of coating liquid;
 means for moving the yarn end axially of its length transversely across the trough in contact with said tube and with said elongated surface area of liquid, said means also simultaneously moving the yarn end back and forth along the length of the trough to cause the yarn end to roll;
 a source of supply for said coating liquid;
 means to meter the coating liquid from said source of supply to said chamber at a predetermined rate at least sufficient to replace coating liquid applied to the yarn end; and
 a planar plate member fixedly attached to said tube along the side of said trough from which the yarn end is discharged, said planar plate member having an upper surface extending in a plane substantially tangential to

said tube adjacent said trough, said planar plate member being at least as wide as the length of said trough whereby the yarn end in its back and forth movement is always in contact with said plate member so that the coating liquid picked up by the yarn end is evenly distributed about the outer surface of the same.

2. A system as claimed in claim 1, in which said source of supply of liquid is under a predetermined pressure.

3. An apparatus as claimed in claim 2, including means to 10 selectively vary the predetermined pressure of liquid in said source of supply, whereby said metering means may be selectively controlled to the predetermined rate of flow of liquid to said chamber.

4. A system as claimed in claim 3, including means positioned beneath said liquid applicator for collecting excess liquid discharged therefrom when no yarn end is running over said trough.

5. A system as claimed in claim 1, in which said yarn end moving means includes a winding machine having a supply 20 package, a takeup package and means to rotate said takeup package to draw the yarn end from said supply package;
 said liquid applicator being positioned intermediate said packages.

6. A system as claimed in claim 1, in which said means to 25 supply liquid under pressure to the chamber of said tube includes metering means and a pressure regulator selectively operable to control metering of liquid by said metering means to the chamber of the tube and from the chamber to a predetermined rate.

30 7. A system as claimed in claim 1 wherein said planar plate member is substantially trapazoidal in plan elevation and diverges from said tube.
